Application November 24, 1934, Serial No. 754,579
Renewed July 18, 1938

9 Claims. (Cl. 29—21)

The principal objects of this invention are to provide an improved means and method for introducing a stereotype plate into a shaving or cooling device by distorting it in such a way as to prevent the rubbing of the type surface against the arch; to provide improved means for clamping the plate in the arch; to provide a method of finishing and cooling the plate which consists essentially in properly clamping the plate first in a shaving arch and then in a cooling arch and performing the desired operation on the plate while it is firmly held therein so that all the strains of cooling will be resisted by a firm pressure, thus giving the finished and cooled plate a true and accurate shape; to provide a new and useful means for moving the plate from a loading platform to the shaving arch, from the shaving arch to the cooling arch, and from the cooling arch to the delivery stand; to provide means for pinching the edges of the plate together, lifting it up into either arch and then releasing the pinch on the bottom edges; to provide the pinching means in such form that it will pinch the plate in its lowered position and release it in the arch and vice versa; to provide means for lifting the plate into the shaving arch by a motion which insures that the plate will come firmly up against the arch before the edges previously pinched are released; to provide means whereby, as each plate is brought underneath the cooling arch it is effectively clamped therein, cooled, and discharged before the next plate arrives, and to provide for pushing the plate off the conveyor to deliver the plate to the means for carrying the plate off out of the machine.

Other objects and advantages of the invention will appear hereinafter.

Reference is to be had to the accompanying drawings, in which

Fig. 1 is a longitudinal central cross sectional view of a plate finishing and cooling machine constructed in accordance with this invention;

Fig. 2 is an end view thereof, taken in the direction of the arrow 2 in Fig. 1;

Fig. 3 is an end view of the plate receiving arch and associated parts, as shown in Fig. 2;

Fig. 4 is a sectional view on the same line as Fig. 1 showing the loading platform and shaving arch;

Fig. 5 is a fragmentary view of a stop carried by the conveyor for properly loading the plate beneath the shaving arch;

Fig. 6 is a detail side elevation of the receiving platform;

Fig. 7 is a plan view of the receiving platform and conveyor bar;

Fig. 8 is a similar view of the conveyor and certain associated details;

Fig. 9 is a side elevation of the end of the conveyor bar and the delivery end of the conveyor bar and associated parts;

Fig. 10 is a sectional view on the line 10—10 of Fig. 8;

Fig. 11 is a cross section on the line 11—11 of Fig. 1, showing the shaving operation and showing only one of two cams located on the same axis;

Fig. 12 is a similar view showing the other cam, but in the same position;

Fig. 13 is a sectional view of one end of the shaving arch showing the position of the pincher bar;

Fig. 14 is a sectional view of the cooling arch on the line 14—14 of Fig. 1;

Fig. 15 is a similar view showing the parts in a different position;

Fig. 16 is an end view at the cooling end of the machine, as indicated by the arrow 16 in Fig. 1, and

Fig. 17 is an enlarged sectional view of the cooling end of the machine on the same plane as Fig. 1.

The finishing of stereotype printing plates for newspaper presses must be done not only expeditiously but with extreme accuracy. After a stereotype printing plate is cast, it is the usual practice to shave the ribs on the concave side of the plate and thereafter cool the plate before sending it to the press. Reasonably satisfactory equipment is available in the present market for shaving the plates. There is, however, no suitable equipment available for properly cooling the plates and holding them in proper shape so that they will be true when cooled. By this invention I provide means for holding the plate while it is being cooled so that it cannot warp out of shape in the cooling action and also include effective means for clamping the plate in the arch.

In this invention the shaved plate is clamped between two concentric surfaces and a cooling medium is applied to both sides of the plate while it is firmly held. In this way all the strains produced by cooling are resisted by a firm pressure so as to leave the finished and cooled plate in its true shape.

In the form shown, a box-like frame 1 constitutes the principal framework of the machine on which are bolted a shaving arch 2 and a

cooling arch 3. Through a motor support bracket 4, secured to the frame 1, a motor 5 is mounted. A pinion 6 is mounted on the shaft of the motor armature and meshes with a gear 7 which is secured to a cross shaft 8. The latter is mounted by ball bearings 9 and 10 in the frame 1 and secured therein by seals 11 and 12. The right hand end of the cross shaft 8, as viewed in Fig. 2, carries a barring hub 12* which may be used to 10 rotate the mechanism manually. The central part of the cross shaft 8 mounts a worm 13 firmly secured thereto which meshes with a worm wheel 14 which is concentrically mounted on the end of, and keyed to, a sleeve 15, the latter being 15 rotatably carried on a shaft 16. The finished outer surface of the sleeve 15 cooperates with a bearing 17 which forms part of the machine frame 1. A shear pin hub 18 is keyed to the shaft 16 by a key 19 and cooperates with the 20 sleeve 15 through a shear pin 20. This provides a safety device in case of unusual strain in the machine so that the shear pin 20 may be broken without causing damage.

The left hand end of the shaft 16, as viewed 25 in Fig. 1, has a heavy pinion 21 mounted thereon which meshes on the one side with a gear 22 carried by a knife bar shaft 23 and on the other with a gear 24 secured to the end of a shaft 25. The shaft 25 serves as the principal drive shaft 30 for operating the different mechanisms in their proper sequence while the knife bar shaft 23 operates the duplex knife 33-34 for finishing off the ribs on the concave side of the plate. The knife bar shaft 23 is mounted in preloaded bearings 26 by properly bored holes in the frame 1 and secured therein by caps 28 and 29 respectively. In order to provide a sturdy construction, the two ends of the knife bar shaft 23 preferably constitute stubs of a solid casting. 35 which is shown as a knife bar 30 carrying two projections 31 and 32 on which are mounted knives 33 and 34 by bolts 30* and provided with the customary adjusting screws 35.

It will be noted that the shaving arch 2 and 45 cooling arch 3 are made of a larger diameter than is necessary to take the ordinary sized plate and that water jacketed liners, or inside arches, 36 and 37 are provided to give the proper inside dimension. This has its utility not only in providing a separate water jacket but it also permits construction of a standard machine with the capability of easily changing the liners for others to accommodate different sized plates. A 50 chip box 38 fits in an opening in the front end 55 of the frame 1 and provides a container for receiving the chips from the shaving knives 33 and 34.

Running essentially the full length of both arches and mounted on the frame 1 by suitable 60 brackets are shafts 39, 40, 41 and 42 providing support for mechanism which pinches the plate in as it is lifted into the arch and mounting the mechanism which lifts the two ends of the plate in each of the arches. It is to be understood 65 that a similar mechanism operates on the plate when it is lifted into the cooling arch as is used when the plate is lifted into the shaving arch. This improved mechanism has for its purpose the provision of a motion which insures 70 the plates being set firmly up against the arch before the pinched edges are released, thereby preventing any burnishing of the type as is present in machines now on the market. This is accomplished by pinching the opposite straight 75 edges of the plate together, lifting it up, and

then releasing the pinch on the bottom edges. The lifting and pinching is performed by notched bars 43 and 44, projections on which supplement notches in conveyor bars 45 and 46 respectively. The pincher bar 43 has, in the present embodiment, two arms integral therewith which are pivotally mounted on studs 47 carried on the free ends of arms 48, the arms 48 being secured to the shaft 39. Also secured to the shaft 39 is an arm 48* which carries a poppet 50 rotatably secured thereto which is penetrated by a threaded rod 51 carrying jam nuts 52. The threaded rod 51 forms part of a link 53, the other end of which is pivotally secured to a lever 54 which is pivoted on the shaft 41 and the other end of which is pivoted on a cam yoke 55. The cam yoke 55 rotatably mounts a cam roller 56 which cooperates with a cam path 57 in a cam 58 fixed to the shaft 39. The cam yoke 55 has a machined inner oblong surface 59 cooperating with a hub 60 of the cam 58 to thereby guide and locate the cam yoke 55. At the left hand end of the cam yoke 55, as viewed in Fig. 11, a lever 61 is pivotally connected to the yoke 55, said lever being pivoted on the shaft 42. The other arm 62 of the lever 61 is pivotally connected to a link 63, the outer end of which is in the form of a threaded rod 64 carrying jam nuts 65 and piercing a poppet 66 carried on the end of an arm 67*. The arm 67* is secured to the shaft 40 which shaft also mounts arms 67, the free ends of which are pivotally connected by studs 68 to the pincher bar 44. Thus, with any rotation of the cam 58 such that the cam roller 56 is moved, motion will be imparted through the two mechanisms just described to move both pincher bars 43 and 44 toward or away from the plate. This mechanism may, therefore, be used to pinch the plate in its lowered position and release it in the arch and also the reverse; viz, pinching the plate before it is moved down and releasing it in its lowered position. Since pincher bars 43 and 44 are pivoted at points 47 and 68 it is necessary to guide the outer ends to obtain a definite practicable motion. Two toggle bars 69 are pivotally connected by studs 70 to the pincher bar 43. Toggle bars 69 penetrate poppets 71 and mount springs 72 and lock nuts 73. The poppets 71 are pivotally mounted in projections on the arm 74 which is secured to the shaft 41. Arms 75 and 76 are secured respectively to the shafts 41 and 42 and pivotally attached to the two ends of a second cam yoke 77. The cam yoke 77 rotatably mounts a cam roller 78 which cooperates with a cam path 79 in a cam 80 which latter is secured to the cam 58. An inner finished oblong surface 81 of the cam yoke 77 cooperates with a second hub 82 of the cam 58, thereby guiding and locating the cam yoke 77 and permitting an oscillatory motion to be imparted to the shafts 41 and 42 from the cam 80. It is apparent that the toggle links 69 may be used to lift and lower the pincher bar 43. A similar arrangement lifts and lowers the pincher bar 44. This constitutes the mechanism necessary for pinching the straight edges of the plate together, lifting it in the arch, releasing it and after the plate is finished pinching it together, lowering it and releasing it. It is to be understood that a similar pinching and lifting arrangement preferably is used in the 70 cooling arch 3 by utilization of the motion already provided in shafts 39 and 40, 41 and 42 without duplicating the cams and link mechanism just described.

It will be noted that the shaft 25 is held in 75

position endwise by the gear 24 and a collar 83. The left hand end of the shaft 25, as viewed in Fig. 1, is supported by a bushing 84 in the frame 1 and is bored to receive the shaft 85. The shaft 85 is mounted in a bushing 86 which latter is carried in the frame 1 and in a removable bearing 87 also carried in the frame 1, with the left hand end of said shaft, as viewed in Fig. 1, being supported by a cover 88. A key 89 serves to secure the cam 58 to the shaft 85 and also angularly fixes that shaft to the shaft 25 from which it derives its rotary motion.

A segment arm 90 is pivoted on the shaft 85 by bushings 91 and 92 and is provided with a pair of bifurcated projections 93 and 94 which, through studs 95 and 96, pivotally mount one end of each of a pair of lift rods 97 and 98 respectively for the cooling saddle 111. Each of these lift rods pierces a non-rotatable shaft 99 and is provided with a shoulder 100 for bearing against one end of a spring 101, the other end of which presses against a washer 102. A washer 103 is provided to bear against the top side of the shaft 99 and a check nut 104 is threadedly secured one each on the ends of the lift rods 97 and 98. The shaft 99 is mounted in a bracket 105 which has a downwardly extending yoke 106 for cooperation with a finished surface 107 of the segment arm 90. The outer ends of the shaft 99 mount rollers 108 and 109 which cooperate with vertical slots carried respectively in the cap 29 and a stop support 110. A cooling saddle 111 is securely mounted on the bracket 105 and carries a water jacket chamber 112 and spray holes 113 which may be used to place a liquid cooling medium on the plate P while it is locked in the cooling arch 3. The liner 31, which is secured in the cooling arch 3, also carries a water jacket chamber 114 and spray holes 115 which may be used to place a liquid cooling medium on the convex surface of the plate P. These cooling mediums may be applied to the plate P simultaneously or independently as desired. It is evident that in moving the saddle 111 from the position shown in Fig. 15 to that shown in Fig. 14 the saddle will describe a vertical course neatly fitting in the concave side of plate P. This is insured through the yoke-like projection 106 cooperating with the surface 107 and the rollers 108 and 109 traveling in vertical slots.

It is apparent that the plate P may be placed in the arch 3 by the pinching and lifting mechanism described above after which the saddle 111 may be forced against the concave side of the plate under the pressure of the springs 101 and firmly held there while being cooled. The lifting of the saddle 111 may be accomplished through the mechanism just described in cooperation with teeth 116 carried by the segment arm 90 cooperating with a segment 117 secured to a shaft 118. The shaft 118 is mounted by bushings in the frame 1 and an end bracket 119 and carries an arm 120 secured to its left hand end as viewed in Fig. 1. The free end of the arm 120 is pivotally secured by a stud 121 to a yoke arm 122. On the arm 122 is rotatably mounted a cam roller 123 cooperating with a cam 124 securely mounted on a barrel cam 125 which latter is secured to and rotates with the shaft 85. The barrel cam 125 has a hub 126 finished to cooperate with a yoke 127 of the arm 122. It guides the motion of that arm in conjunction with that imparted by the cam 124. It is apparent that the cam 124 may be so designed as to oscillate the segment 117 and impart a lifting and lower-

ing motion to the saddle 111 so that, as each plate is brought underneath the cooling arch 3, it is clamped therein, cooled and discharged before the next plate arrives. A skirt 127a is secured to the bracket 105 which serves to protect the working mechanism from a cooling medium, such as water, which courses down the outside of said skirt and may be led away by a drain pipe attached to an outlet 128. A stud 130 carried in the cover 88 pivotally mounts a cam segment 131 on which is rotatably carried a cam roller 132 for cooperating with a slot 129 of the barrel cam 125. Meshing with the teeth of the cam segment 131 is a pinion 133 integral with a gear 134 which latter meshes with a gear 135. Gears 133-134 and gear 135 are mounted, the former by a stud 136, the latter by a shaft 137 extending transversely across the machine and to which the gear 135 is secured. The gear 135 and a collar 138 serve to prevent end motion of the shaft 137. Secured to the shaft 137 are pinions 139 and 140 which mesh with rack teeth carried on the bottoms of the conveyor bars 45 and 46 respectively. Since the barrel cam 125 is secured to the shaft 85 the cam slot 129 may be so designed as to cooperate with the mechanism just described and move the conveyor bars 45 and 46 longitudinally to properly convey the plates from the loading position to the shaving arch, from the shaving arch to the cooling arch and from the cooling arch to the delivery end of the machine.

As shown in Fig. 9, when the plate P is moved to the delivery end of the finishing machine a spring-seated stop 141 is depressed as the plate goes by and serves to push the plate off conveyor bars 45 and 46 as they are returned and thereby delivers the plate to a set of inclined rollers 142 which may be used to carry the plate off to the press room by gravity. In Fig. 4 the right hand ends of conveyor bars 45 and 46 carry each a stop 143 pivoted thereon and backed up by a spring 144 to prevent bouncing as this stop comes in contact with the plate P to move it underneath the shaving arch.

Fig. 5 demonstrates the manner in which these stops pivot under the plate on the receiving platform as the bars go to the right, as viewed in Fig. 1.

Mounted on the receiving platform 148 are a series of supports 145 spring-seated in a clockwise direction as shown in Fig. 7. These projections tend to bridge the slot in which the conveyor bars ride. It will be seen in Fig. 8, however, that as the conveyor bar 45 travels to the right it presses the projections 145 aside to permit the plate P to rest down on the conveyor bar 45. This is shown in Fig. 7. Thus the plate is supported by projections 145 until such time as the conveyor bars travel beneath the plate and receive it ready for motion underneath the shaving arch. Fig. 7 shows the projections 145 when the conveyor bars 45 and 46 are at their extreme right hand position.

Figs. 6 and 10 show the assembly of this mechanism with the springs 146 attached each at one end to the receiving platform 148 and at the other end to an arm 147. They tend to rotate the projections 145 in a clockwise direction. A similar but opposite hand arrangement is provided to serve the conveyor bar 46.

It will be seen that by this invention means is provided for conveying a comparatively thin plate into a shaving arch which fits the plate, for clamping it in the arch rigidly and for cooling the plate simultaneously with the finishing

of its surface. Also means is provided for automatically conveying the plate out of the shaving arch into the cooling arch and cooling it on both sides in a positively clamped position between two concentric surfaces that fit the plate so that the cooling of both sides of the plate, while firmly held, will not result in the distortion of the plate by cooling because all the strains of cooling are resisted by a firm pressure. Thus 10 the plate comes out finished and cooled in a true shape. This involves a new and useful means for moving the plate from the loading platform to the shaving arch, from the shaving arch to the cooling arch, and from the cooling arch to the delivery stand. The plate is prevented from 15 bouncing when the conveying means comes into contact with the plate for starting it through the machine. Also, provision is made for accomplishing the above mentioned purposes by pinching 20 the straight edges of the plate toward each other and releasing them after the plate is nested in the arch, thus preventing the burnishing of the type, which is an ordinary fault of the machines now on the market. The sequence of 25 operations is as follows:

The straight edges of the plate are pinched in its lowered position, the plate is raised and then the pinching means is released. The plate is again pinched before it is moved down, lowered, 30 and then released. All these operations are automatic after the plate is placed on the loading table.

This invention involves the above described machine as well as the method of shaving and cooling cast plates.

Having thus described my invention and the advantages thereof, I do not wish to be limited to the details herein disclosed, otherwise than as set forth in the claims, but what I claim is:

1. In a stereotype plate cooling machine, the combination of an arch having an internal configuration for fitting the exterior of a shaved printing plate, a saddle in the arch having an outer surface for fitting the interior of the shaved printing plate, means for moving the plate between the saddle and arch longitudinally, means for then contracting the plate by moving its opposite edges toward each other, means for moving the saddle radially fully into the arch to clamp the plate thereagainst, means for cooling the plate, means for withdrawing the saddle, means for again operating the contracting means to contract the plate, and means for moving the plate out of the arch.

2. In a stereotype plate cooling machine, the combination of an arch having an internal configuration for fitting the exterior of a shaved printing plate, a saddle in the arch having an outer surface for fitting the entire interior of the shaved printing plate, means for contracting the plate by moving its opposite edges toward each other, means for then moving the plate radially to a seat in the arch, means for then releasing the edges of the plate, means for finally moving the saddle fully into the arch to clamp the plate thereagainst, and means for cooling the plate.

3. In a machine of the character described, the combination of an arch for receiving stereotype printing plates, levers at the sides of the arch having surfaces for supporting the straight edges of the plate and having surfaces for engaging the sides of said straight edges, pivots on which said levers are mounted, means for swinging the levers on said pivots inwardly to force the straight edges 75 of the plate toward each other, each lever being

mounted to swing on another axis, and means for swinging the levers on the second axis in a direction to move their supporting surfaces in a radial direction toward the arch and seat the plate therein while in contracted condition.

4. In a device for manipulating the edge of a stereotype printing plate, the combination with an arch for receiving a printing plate of a shaft at the side of the arch having an arm thereon, a cam for oscillating said shaft, a member pivoted to said arm, a pivot carried by said member, a lever mounted to swing on the said pivot and having a surface for supporting the edge of the printing plate in the arch and another surface for engaging the side of said edge, and means for moving said lever to cause the latter surface to force the edge of the plate inwardly.

5. In a machine of the character described, the combination of an arch for receiving a stereotype printing plate, levers on each side of the arch, said levers having surfaces for supporting the straight edges of the plate and being provided with projecting surfaces adapted to engage the sides of said straight edges of the plate, means for moving said levers inwardly to contract the plate, means for moving said levers to force the plate into the arch in its contracted condition, a saddle within the arch, and means for forcing the saddle into the arch to firmly clamp the plate therein.

6. In a machine of the character described, the combination of an arch fitting the outside surface of a curved printing plate, means for contracting the plate at its straight edges, means for moving the plate in its contracted condition into the arch, means for shaving the interior of the plate, means for again contracting the plate, means for withdrawing the plate from the arch, a second arch having a concave surface for fitting the printing plate, means for moving the plate from the first arch to the second arch, means for contracting the plate after it is moved to the second arch, means for moving the plate into the second arch, means for cooling the plate in the second arch, means for again contracting the plate, and means for moving the plate from the second arch.

7. In a machine of the character described, the combination of an arch fitting the outside surface of a curved printing plate, means for contracting the plate at its straight edges, means for moving the plate in its contracted condition into the arch, means for shaving the interior of the plate, means for preliminarily cooling the plate while it is being shaved, means for again contracting the plate, means for withdrawing the plate from the arch, a second arch having a concave surface for fitting the plate, means for moving the plate from the first arch to the second arch, means for contracting the plate after it is moved to the second arch, means for moving the plate into the second arch, means for cooling the plate in the second arch, means for again contracting the plate, and means for moving the plate from the second arch.

8. In a machine of the character described, the combination of an arch fitting the outside surface of a curved printing plate, means for contracting the plate at its straight edges, means for moving the plate in its contracted condition into the arch, means for shaving the interior of the plate, means for again contracting the plate, means for withdrawing the plate from the arch, a second arch having a concave surface for fitting the printing plate, means for moving the plate from

the first arch to the second arch, means for contracting the plate after it is moved to the second arch, means for moving the plate into the second arch, means for cooling the plate in the second arch, means for again contracting the plate, a shaft, and means operated by the shaft for actuating all of the contracting means.

9. In a machine for finishing and cooling stereotype printing plates, the combination with a loading platform on which the plates are adapted to be placed, resting on their straight edges, said plat-

form having a pair of grooves along it, a conveyor bar in each groove, a series of pivoted supports along the grooves projecting into them, means for yieldingly holding the supports over the grooves to support the edges of the plate above the conveyor bar, means on the conveyor bars for engaging the rear edge of a plate and moving the same along with the conveyor bars, and means for reciprocating said conveyor bars to move the plates forward at each forward motion thereof. 10

HENRY A. WISE WOOD.
